UNITED STATES PATENT OFFICE

140,395

DESIGN FOR AN ICE CRUSHER

Henry J. Talge, Kansas City, Mo., assignor to John C. Hockery, Foster L. Talge, and Henry J. Talge, doing business as Rival Manufacturing Company, Kansas City, Mo.

Application November 22, 1944, Serial No. 116,497

Term of patent 14 years

(Cl. D89—1)

To all whom it may concern:

Be it known that I, Henry J. Talge, a citizen of the United States, residing at Kansas City, Jackson County, State of Missouri, have invented a new, original, and ornamental Design for an Ice Crusher, of which the following is a specification, reference being had to the accompanying drawing, forming part thereof, in which

Fig. 1 is a side elevational view of an ice crusher embodying the design;

Fig. 2 is a front elevational view; and

Fig. 3 is a top plan view.

I claim:

The ornamental design for an ice crusher, as shown.

HENRY J. TALGE.
